(57) **CLAIM**

The ornamental design for a identification image scanner and router, as shown and described.

DESCRIPTION

FIG. 1 is a front perspective view of a identification image scanner and router showing our new design;

FIG. 2 is a front view thereof;

FIG. 3 is a rear view thereof;

FIG. 4 is a right side elevational view thereof; a left side elevational view being a mirror image of the right side elevational view,

FIG. 5 is a top plan view thereof;

FIG. 6 is a bottom plan view thereof; and,

FIG. 7 is a front perspective view thereof with the cover open.

The broken line in the drawings is for illustrative purpose only and forms no part of the claimed design.
